AUTOMATIC TRAIN-PIPE COUPLING

1,081,125.

Specification of Letters Patent

Patented Dec. 9, 1913

Application filed February 7, 1912. Serial No. 676,094

To all whom it may concern:

Be it known that I, WILLIAM D. LEFF-
WICH, a citizen of the United States, resid-
ing at Wilkinsburg, in the county of Alle-
5 gheny and State of Pennsylvania, have in-
vented a new and useful Automatic Train-
Pipe Coupling, of which the following is a
specification.

The invention relates to improvements in
10 automatic train pipe couplings.

The object of the present invention is to improve the construction of automatic train pipe couplings, and to provide a simple, efficient and comparatively inexpensive coupling, adapted to automatically lock the respective members or coupling heads of the coupling together and for opening the valves of the brake, signal and heating pipes of a train, when the cars are coupled, and capable of automatically unlocking the coupling heads or members and of closing the valves of the train pipes when the cars are pulled apart.

25 A further object of the invention is to provide a train pipe coupling of this character, capable of vertical, lateral and longitudinal movement to adjust itself to the various movements of the cars of a train in motion, without affecting the mechanism for locking the coupling heads or members together.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a side elevation, partly in section, of an automatic train pipe coupling, constructed in accordance with this invention. Fig. 2 is a horizontal sectional view on the line 2—2 of Fig. 1. Fig. 3 is a similar view, taken substantially on the line 3—3 of Fig. 1. Fig. 4 is a transverse sectional view on the line 4—4 of Fig. 2. Fig. 5 is a transverse sectional view, taken substantially on the line 5—5 of Fig. 2. Fig. 6 is a detail sectional view on the line 6—6 of Fig. 1. Fig. 7 is an enlarged detail sectional view, illustrating the construction of the gasket casings.

Like numerals of reference designate corresponding parts in all the figures of the drawings.

In the accompanying drawings in which is illustrated the preferred embodiment of the invention, the automatic train pipe coupling comprises in its construction two similar co-acting coupling heads or members 1, each carried by a supporting bracket 2 located beneath and extending longitudinally of the shank or draw bar 3 of a car coupling 4. The supporting bracket 2 is provided at its rear portion with an upwardly extending enlargement or ear 5, which is pivoted by a transverse bolt 6 between a pair of depending flanges or ears 7 of a hanger 8. The ears 7 are connected at the top by horizontal portions 9 from one side of which projects a vertical portion 10, having a horizontal flange 11 arranged above and in spaced relation with the horizontal top portion 9, and secured to the rear end of the shank or draw bar 3 at the bottom of the same by a vertical bolt 12, which forms a pivot for the hanger to permit horizontal rotary movement thereof. The bolt 6 forms a horizontal pivot for the supporting bracket, which is adapted to swing upwardly or downwardly on the bolt 6, and longitudinally on the vertical bolt 12 to permit the train pipe coupling head or member 1 to adjust itself to the movement of the cars, so that the motion of the latter will not affect the joints or connections formed by the train pipe coupling.

The supporting bracket 2 is provided at the front and back with depending guides 13 and 14, having alined openings for the reception of a slidable bar 15, secured at its outer end in a socket 16 of the coupling head or member 1 by a transverse bolt 17, or other suitable fastening means, whereby the coupling head or member 1 is mounted on and carried by the slidable bar. The front portion of the slidable bar is oblong in cross section and the opening of the guide conforms to the configuration of the same. The slidable bar is provided with a round rear portion 18, extending through the rear guide 14, which is provided with a corresponding opening. The round rear portion 18, which is threaded at its rear end to receive a nut 19, supports a coiled spring 20, located in advance of the rear guide 14 and interposed between the same and the shoulder formed by the polygonal front por-

tion of the slidable bar and yieldably urging the slidable bar and the coupling head or member outwardly. The nut 19 forms a stop and is adapted to engage the inner or rear face of the guide 14 to limit the outward movement of the slidable bar.

Each coupling head or member is provided at one side with an integral tapered socket or loop 21 and having at the opposite 10 side a forwardly projecting tapered point or guiding arm 22, adapted to fit in the loop or socket of a corresponding train pipe coupling head, as clearly illustrated in Fig. 2 of the drawings. The loop or socket 21, 15 which is horizontally disposed, is open at the front and back to permit the arm 22 of the co-acting coupling head or member to extend entirely through it, as shown, and the guiding arm 22, which is tapered vertically 20 and horizontally, is preferably flanged, as shown, but it may be of solid formation, and it presents an inner flat face 23 to the flat face 24 of the co-acting coupling head or member. The outer end of the arm 22 is 25 beveled at the inner side at 25, the point being laterally off-set from the plane of the side face 24. The upper, lower and outer faces of the projecting guiding arm fit against the socket or loop at the top, bottom 30 and outer portions of the same, and the parts are held against vertical and lateral movement on each other when in their interlocked relation, the relative inward lateral movement being resisted by locking levers 26. 35 The locking lever 26, which is horizontally disposed, is provided with an approximately segmental head 27, mounted on a vertical pivot 28 in a horizontal transversely disposed slot or opening 29 of the coupling head 40 or member and located at the inner end of the projecting arm thereof, as clearly illustrated in Fig. 2 of the drawings. The projecting arm is provided at its inner flat face with a horizontally disposed segmental recess 30 having an inner curved wall, which 45 is located opposite the opening 29 when the two coupling heads or members are in their interlocked relation. When the parts are 50 in proper position with the outwardly extending arm in contact with the outer portion of the loop or socket, the curved wall of the recess 30 is arranged concentric with the pivot 28, and the peripheral edge of the locking lever is adapted to engage the curved 55 wall 30, the oscillation of the locking lever carrying the curved edge of the head thereof into and out of the recess 30. When the 60 segmental head of the locking lever is engaged with the recess 30 of the projecting arm, the latter will be forced tightly against the outer side of the loop and will be securely locked therein, so that any longitudinal movement of the car couplings and the consequent longitudinal play or vibration of 65 the slidable bars of the train pipe couplings

will not affect the tight connection of the interlocked members or couplings 1. The segmental head is cut-away at the rear or inner side so as to enable the head through its rotary movement to be returned within the horizontal slot 29 from its projecting position, so as to release the projecting arm and permit a separation of the coupling heads or members 1. The locking lever has an outer portion or arm projecting laterally 70 from the coupling head or member 1, and extending forwardly at a slight angle to the coupling head or member 1 when the head of the lever is in engagement with the projecting arm. When the outer portion or arm of the lever is swung rearwardly from the position shown in full lines in Fig. 2 of the drawings to the position illustrated in dotted lines of the said figure, the segmental head is withdrawn from its engaging position. 80

The outer portion of the locking lever of each of the coupling heads or members is connected by a link or bar 31 with the front guide 13 of the supporting bracket 2, so that the longitudinal movement of the slid- 90 able bar 15 through the guides 13 and 14 will automatically oscillate the locking lever. When the slidable bar 15 moves outwardly through the guides, the lever is carried outwardly and through its relatively fixed connection with the link or bar 31 is caused to oscillate on its pivot 28, the outward sliding movement of the bar 15 being the equivalent of a rearward pull on the outer portion of the locking lever and operating to 100 swing the locking lever from the position shown in full lines in Fig. 2 to that shown in dotted lines. When two cars come together for coupling, the locking lever is swung in the opposite direction and is carried from the position shown in dotted lines in Fig. 2 to that illustrated in full lines. The link 31 is pivoted to the outer end of the locking lever 26 by a pin 32, and the inner or rear end of the link is laterally 110 curved and bifurcated to straddle a horizontal flange 33, formed integral with the guide 13 and having a longitudinal slot 34 in which slides the pivot pin 35. The slidable movement of the pivot 35 in the slot prevents any variation in the size of the car 115 couplings from interfering with the operation of the locking levers, and the segmental shape of the heads thereof and the recess 30 also compensate for variations in the size of the car couplings, as it is not necessary that the segmental projecting portions of the locking levers should entirely fill the segmental recesses 30 in the inner faces of the projecting guiding arms, as it is only 120 necessary that the heads of the locking levers project into the recesses 30 in order to securely lock the coupling heads or members together.

The front pivot pin 32 projects at the top 13

above the outer end of the locking lever, which is bifurcated to receive the link 31, and the latter is provided at an intermediate point with a vertical projection 36, extending upwardly, as clearly shown in Fig. 1. The vertical projection 36 preferably consists of a pin or bolt, having a threaded lower end piercing the link or bar 31 and provided at its lower face with a nut. The front projection 32 and the projection 36, which is spaced from the front projection, are adapted to alternately actuate an arm 37 of a vertical valve stem or body 38, whereby the means for actuating the locking levers will also operate valves 39, 40 and 41 for controlling the passage through the train pipes 42, 43 and 44. The coupling head or member is provided at its upper portion with passages 45 and 46, and at the lower portion with a bottom passage 47. In practice the upper passages 45 and 46 will be arranged to form continuous passages for the signal and for the brake, and the lower passage for the steam, and any preferred arrangement may, of course, be employed.

The valves 39, 40 and 41 may consist of ports or openings formed in the valve body or stem, as illustrated in Fig. 5 of the drawings, or they may be of any other preferred construction, and when the body or stem is rotated, the valves are simultaneously operated. The inner or rear portion of the coupling head or member 1 is provided with upper and lower laterally projecting portions 48 and 49 containing the rear portions of the longitudinal passages and provided with projecting nipples 50, 51 and 52 for the reception of flexible tubes 53, 54 and 55, which connect the passages with the train pipes 42, 43 and 44 and permit the relative movements of the train pipe coupling and the car body. The flexible connections are provided with ordinary hose couplings 56 to render the automatic train pipe coupling interchangeable, so that a car equipped with the same, when necessary, may be coupled to a car provided with the ordinary hose coupling. The nipples are shown extending from the same side of the train pipe coupling head or member, and the flexible connections extend to a bracket 57 fixed to and depending from one side of the car and supporting the adjacent ends of the train pipes 42, 43 and 44, but any other preferred arrangement of pipe connections may, of course, be employed.

The coupling heads or members of the train pipe coupling are equipped at their outer or front faces with upper and lower gasket casings 59, each slidably mounted in grooves or ways 60 and provided at one side with a projecting nipple 61 and having an opening 61^a at the opposite side to receive a nipple of a co-acting coupling head

or member. The slidable casing is detachably secured in place by means of a bolt 62, or other suitable fastening device, and it covers a removable gasket 63, consisting of a plate or piece interposed between the gasket casing and the front or outer face of the coupling head or member. The gasket is provided with openings 64 and 65, which register with the adjacent passages of the coupling head or member and with a bore 70 or opening of the nipple 61 and the opening 61^a of the gasket casing, and the gasket is provided at the opening 65 with an outwardly projecting annular flange or portion 66, which extends through the opening 61^a, so as to surround and yieldably engage a co-acting nipple when the same passes through the opening 61^a to form an air or steam tight connection. The nipple is tapered exteriorly so as to wedge itself in the opening 61^a and compress the elastic gasket.

The upper passages are connected by the nipples and the openings of the upper gasket casings, and the lower passage 47 is provided at its outer portion with two branches 67. The branches 67 of one coupling head or member are connected with those of the co-acting coupling head or member by the lower gasket casing 59 by means of the tapered nipples and the openings having the gaskets. Preferably air and steam pipe connections are provided and the locking mechanism, which retains the coupling heads or members in their interlocked relation, will prevent such connections from being broken or interrupted while the cars are coupled.

When the coupling heads or members are separated, they are supported by chains 68, arranged in pairs and secured at their upper ends to the bumpers or dead wood 69 of the cars, and connected at their lower ends to transverse bars 70, which are carried by the supporting brackets 2. The bars 70 are centrally connected with and project laterally from the front or outer ends of the supporting brackets at the tops thereof, but the chains may be connected with the supporting brackets in any other suitable manner. The supporting chains are equipped with coiled springs 71, arranged on the chains and extending the entire length thereof. When the coupling heads or members are uncoupled, they are supported and maintained in proper position for automatic coupling by the spring chains.

When the coupling heads or members of the train pipe coupling are uncoupled, they are held forward or outward in advance of the car couplings through the pressure of the coiled springs 20, preferably about ten inches more or less as the distance may be varied so as to obtain the desired spring pressure on the coupling heads or members when the latter are in engagement or in interlocked relation. During the operation

of coupling, the coupling heads or members come in abutting contact with each other when the car couplings are about twenty inches apart, so that the sliding bars 15 are forced inwardly or rearwardly and the coiled springs compressed by the further movement of the cars toward each other. The sliding movement of the bars 15 in the supporting brackets moves the locking levers to their engaging position and opens the valves. When the cars separate in uncoupling, the coupling heads or members of the train pipe coupling remain in contact until the car couplings are, say, twenty inches apart, and during this outward movement the bars 15 slide in the guides of the supporting brackets and move the locking levers out of engagement and close the valves so that the coupling heads or members are free to separate when the car couplings are moved that distance apart.

The train pipe coupling illustrated in the accompanying drawings is designed for a passenger equipment, but the device may be employed on freight cars, and when so used is not necessary to provide the signal and heating lines, as will be readily understood.

No claim is made in the present application to the gasket casing and gasket.

What is claimed is:—

1. A train pipe coupling including a longitudinally disposed bracket having spaced depending front and rear guides, means arranged at the inner or rear end of the bracket for pivotally supporting the same, flexible supporting means connected with the outer or front portion of the bracket, a bar slideable in the guides, a spring mounted on the bar and engaging the same and the rear guide, a coupling head arranged at the outer end of the said bar and carried by the same and provided at one side with a socket, said coupling head being also provided at the front with a forwardly projecting tapered arm to fit the socket of a coacting coupling head or member, and locking means for retaining the arm in the socket, said means comprising a locking lever pivotally mounted on the coupling head and projecting into the socket, and connections between the lever and the supporting bracket for oscillating the lever when the coupling head moves inwardly or outwardly with respect to the bracket.

2. A train pipe coupling including a coupling head or member having a flat face at one side and provided with a socket, said coupling head or member being also provided at the front with a forwardly projecting arm tapered to fit the socket of a co-acting coupling head or member and having a flat inner side face to fit the flat face of such coupling head or member, and locking means for retaining the arm in the

socket, said means comprising a locking lever pivotally mounted on the coupling head or member and arranged to project from the flat side face thereof, and connections between the lever and the supporting bracket for oscillating the lever when the coupling head or member moves inwardly or outwardly with respect to the bracket.

3. A train pipe coupling including a supporting bracket, a coupling head slidably mounted in the supporting bracket and provided at one side with a loop forming a socket, said coupling head having a transverse opening extending through it and communicating with the socket, a forwardly extending arm adapted to fit in the socket of a coacting coupling head, a locking lever pivotally mounted in the transverse opening of the coupling head and arranged to project into the socket for locking the arm of the coacting coupling head in the said socket, and a link connecting the lever with the supporting bracket.

4. A train pipe coupling including a supporting bracket provided with a flange having a slot, a coupling head or member slidably mounted in the supporting bracket and provided at one side with a socket and having a forwardly projecting guiding arm, a locking lever pivotally mounted in the coupling head or member and arranged to project therefrom, a link pivotally connected with the locking lever and having a pin slidable in the slot of said flange.

5. A train pipe coupling including a coupling head or member having a transverse opening and provided at one side thereof with a socket and having a forwardly projecting arm adapted to fit in the socket of a coacting coupling head and having a recess to register with the opening thereof, a locking lever having a substantially segmental head and pivotally mounted in the opening of the coupling head or member and projecting into the socket for engaging the recess of the arm of a coacting coupling head, and means for oscillating the locking lever for carrying the same to and from its projecting position.

6. A train pipe coupling including a slidably mounted coupling head having a passage, a locking lever mounted on the coupling head and arranged to engage a co-acting head for securing the same to the said coupling head, a valve for the said passage, said valve being provided with a projecting arm, and a link connected at one end to the lever and at the other end to a relatively fixed part and having projecting means arranged at spaced points along the link to actuate the valve operating arm, which extends across the link between the said projecting means.

7. A train pipe coupling including a supporting bracket, a coupling head or mem-

ber slidably mounted in the supporting bracket and having a passage, said coupling head or member being also provided with a socket and having a projecting guiding arm, a locking lever mounted on the coupling head or member, a valve for the passage, said valve being provided with a projecting operating arm, and a link connected with the lever and with the bracket and having spaced projecting means arranged to actuate the operating arm of the valve.

8. A train pipe coupling including a coupling head or member provided at one side with a projecting socket and having a forwardly extending guiding arm adapted to fit the socket of a co-acting coupling head or member, said coupling head or member be-

ing provided above and below the plane of the socket and the arm with a plurality of longitudinal passages, a plurality of valves 20 controlling the passages and having a common stem, a locking lever mounted on the coupling head or member and arranged to project at the side having the socket, and mechanism for operating the locking lever 25 and the valve stem.

In testimony, that I claim the foregoing as my own, I have hereto affixed my signature in the presence of two witnesses.
